SPARK-GAP USED IN WIRELESS TELEGRAPHY.

1,333,789.

Specification of Letters Patent.

Patented Mar. 16, 1920.

Application filed October 15, 1915. Serial No. 56,102.

To all whom it may concern:

Be it known that we, JOSEPH FRÉDÉRIC JULIEN BETHENOD and EMILE FERNAND GIRARDEAU, engineers, residing in Paris, France, 10 Rue Auber, have invented new and useful Improvements in Spark-Gaps Used in Wireless Telegraphy.

This invention relates to radiotelegraphic apparatus wherein the spark-gap circuit is discharged through a condenser. In such apparatus it is difficult to maintain the electrodes of the spark-gap device in good condition, as rapid deterioration ensues by reason of the heavy current of the discharge. One solution of the problem consists in utilizing a plurality of spark-gaps arranged in parallel and dividing the discharge between them but heretofore regular operation of the spark-gaps thus connected, could not be obtained, as one of the spark-gaps generally primes first and therefore carries alone the whole discharge, the others remaining inoperative.

The present invention has for its primary object to insure a perfectly synchronous operation of the spark-gaps arranged in parallel, the action of the apparatus being based upon the principle that rendering operative the spark-gap having the lowest discharge potential, involves by inductive action, the priming of the other spark-gaps, thereby increasing, to a considerable extent, the difference of potential between their electrodes.

Figure 1 shows by way of example, a diagram of the apparatus in accordance with this invention in which two spark-gaps E and E' are shown arranged in parallel in an oscillatory circuit L C, the condenser C being charged periodically in accordance with any known method. Fig. 2 illustrates a modification in which an auxiliary circuit primes the main discharge.

In the drawing each spark-gap E E' is shown as being connected in series with inductances 1 and 1', respectively which possess between them a co-efficient of mutual induction as high as possible, under these conditions, if the connections are made in such a manner that for currents circulating in the same direction in the two branches of the oscillatory circuit, the two inductances 1 and 1' produce electromagnetic actions of opposite sign; it is possible to demonstrate theoretically and prove experimentally that, for instance, the priming of the spark-gap

E' invariably involves the priming of the spark-gap E even if the distance between their electrodes is different.

As a second application of the invention, the following may be cited: In order that the system illustrated in Fig. 1 should operate, it is not necessary that the two spark-gaps E and E' should be traversed by the same energy; one of them, E' for instance, can serve as an auxiliary spark-gap of small power, intended to regulate the discharge through the main spark-gap E. In this case the inductances 1 and 1' may be unequal and, the current passing through the spark-gap E' may be reduced by connecting in series therewith, an impedance of any kind selected in accordance with the requirements; as to ohmic resistance inductance, and capacity (or an arbitrary combination of these capacities). The whole arrangement may, if desired, be reduced to the arrangement illustrated diagrammatically in Fig. 2, wherein L C E designate the elements of the main circuit, the spark-gap E' being in series with suitable impedance Z. A condenser C' may be connected in series with the impedance Z. The function of the circuit E' Z is to insure an auxiliary priming so to speak of the discharger E so that it acts first; it appears that this auxiliary circuit absorbs stray discharges which tend to destroy the musical character of the emission.

What I claim is:

1. In an oscillatory circuit for wireless telegraphy, a plurality of spark-gaps connected in parallel, each spark-gap being serially connected with an inductance, the several inductances being disposed with respect to each other so as to produce a maximum coefficient of mutual induction.

2. In an oscillatory circuit for wireless telegraphy, a plurality of spark-gaps connected in parallel, each of the gaps being serially connected with an inductance, the inductances being so wound and placed with respect to each other as to produce a maximum coefficient of mutual induction and to produce magnetic fluxes of opposite directions when currents are flowing through the two spark-gaps and branches of the oscillatory circuit in which these spark-gaps are located in the same direction.

3. In an oscillatory circuit for wireless telegraphy, a plurality of spark-gaps connected in parallel, each gap being connected

2
serially with an inductance, the several inductances being disposed so as to produce a maximum coefficient of mutual induction, and one of said spark-gaps being also in serial connection with elements adapted to change the impedance in the pertaining circuit whereby the main discharge through said last named spark-gap will be started.

4. In an oscillatory circuit for wireless telegraphy, a plurality of spark-gaps connected in parallel, each spark-gap being serially connected with an inductance, the inductances being so disposed as to create mutual induction between them, and one of said spark-gaps being serially connected with an auxiliary impedance.

5. In an oscillatory circuit for wireless telegraphy, a plurality of spark-gaps connected in parallel, each spark-gap being connected serially with an inductance, the several inductances being so arranged as to influence each other by mutual induction, and one of said spark-gaps being connected with an auxiliary impedance and with a capacity. 20

25 In testimony whereof we have signed our names to this specification in the presence of two witnesses.

JOSEPH FRÉDÉRIC JULIEN BETHENOD.
EMILE FERNAND GIRARDEAU.
